[57] CLAIM

The ornamental design for a rolling shutter valance, as shown and described.

DESCRIPTION

FIG. 1 is a perspective view of a rolling shutter valance in accordance with our new design showing the top, front and a side thereof.

FIG. 2 is another perspective view of the rolling shutter valance showing the front, bottom and side thereof.

FIG. 3 is a side elevational view of one side of the rolling shutter valance, the opposite side being a mirror image of that shown.

FIG. 4 is a front elevational view of the rolling shutter valance, and

FIG. 5 is a bottom plan view of the rolling shutter valance.

The back side of the rolling shutter valance is plain and unornamented. The broken line showing of a trackway is for illustrative purposes only and forms no part of the claimed design.
